VALVE MECHANISM FOR ENGINES

Farrer Cormier, Welsh, La., assignor of one-third to Ovillian Matt and one-third to Ada Cormier, both of Welsh, La., and one-third to Theobert Cormier, Jefferson Davis Parish, La.

Application March 9, 1938, Serial No. 194,969

4 Claims. (Cl. 121—179)

This invention relates to valve mechanism for engines actuated by compressible fluid, such as steam, the general object of the invention being to provide means for controlling the entrance of the fluid to a cylinder of the engine at one side of the piston thereof and for relieving compression at the opposite side of the piston after the piston passes exhaust, such means acting to retain a sufficient amount of the fluid in the cylinder to act as a cushion at the end of the stroke of the piston. Thus the valve mechanism serves the double purpose of controlling the inlet of the fluid to the cylinder to move the piston in one direction and to relieve compression at the other side of the piston.

Another object of the invention is to so construct and arrange the parts that the invention will be very compact and inexpensive to manufacture and install and maintain in operated position.

A further object of the invention is to provide simple means for manually adjusting the parts to reverse the engine.

This invention also consists in certain other features of construction and in the combination and arrangement of several parts, to be herein-after fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a top plan view of an engine provided with the improved valve mechanism.

Figure 2 is a horizontal sectional view through such engine with the crank shaft end thereof omitted.

Figure 3 is a fragmentary view looking into the valve chest of the engine with the cover plate of the chest removed.

Figure 4 is a view of the inner face of the valve chest cover.

Figure 5 is a view of the outer face of the rotary valve member.

Figure 6 is a section on the line 6—6 of Figure 5.

Figure 7 is a perspective view of the stationary valve disk, with the tubes attached thereto.

Figure 8 is a section on the line 8—8 of Figure 2.

Figure 9 is a perspective view of the outer portion of the shaft which is connected with the rotary valve member.

Figure 10 is a perspective view of a portion of the shaft which fits in the tubular part of the

valve shaft and which carries the cranks for the valve operating links.

In these drawings, the numeral 1 indicates a block which is bored longitudinally to form the cylinder 2 which is closed at one end by the cover 3 and said block is also bored at right angles to the cylinder to form the valve chest 4 which terminates short of the cylinder to leave the wall 5 which is provided with the oppositely arranged and diametrically located elongated slots 6, each of which tapers from its outer end to its inner end, these slots communicating the chest with the cylinder through means of the passages 7 which open out into the cylinder at the ends thereof as shown in Figure 2. A piston 8 is located in the cylinder and the rod 9 thereof passes through a hole in the closed end of the cylinder and through the packing gland 10 carried by said closed end, the rod being connected at its outer end with the cross head 11 sliding in the guides 12 carried by the block and said cross head is connected by the pitman 12' with the crank of a shaft 13. The shaft is journaled in the frame 14, preferably cast with the block. Said shaft carries the usual flywheel 15 and the crank means 16 for 25 the valve actuating links 17.

An exhaust port 18, having a widened inner end 18' is formed in the bottom of the cylinder substantially midway the ends thereof and an exhaust pipe 19 leads from said port.

The rotary valve disk is shown at 20 and its inner face has a ground fit, with the bottom wall 5 of the chest 4 and said disk has a stud shaft 21 projecting from its inner face which extends into a bearing opening 22 in the wall 5 at the center of said wall. A shaft 23 extends from the center of the outer face of the disk 20 and has a socket 24 therein and a segmental projection 25 is formed on the outer end of the shaft 23, see Figure 9. The shaft 23 passes through an opening 26 formed in a boss 27 on the inner face of a cover plate 28 for the chest, the plate being connected to the block by the bolts 29 and said shaft passes through a packing gland 30 carried by the plate 28.

The disk 20 is provided with the arcuate slot 31 therein and with the smaller arcuate slot 32, the slot 32 being made of less width and of less length than the slot 31 and being placed closer to the axis of the disk than is the slot 31. The slot 31 will pass over the enlarged outer ends of the slots 6 in the inner wall of the valve chest during rotary movement of the disk 20 while the slot 32 will pass over the smaller inner ends of said slots 6 during this rotary movement. A 55

groove 33 is formed in the outer face of the disk 20 and forms a continuation of the slot 31, this groove being provided for balancing the disk.

A stationary valve disk 34 has a central hole 35 therein through which the inner end of the shaft 23 passes and a spring 36 holds the disk 34 against the central portion of the disk 20, said disk 34 being of such diameter as to not cover that part of the disk 20 which contains the slot 31 and the groove 33 but covers the part containing the slot 32. The contacting parts of the two disks have a ground fit to prevent leakage between them. The spring 36 bears against the inner end of the boss 27 and a pair of diametrically arranged tubes 37 extend from the outer face of the stationary disk 34 and communicate with holes 38 passing through said disk, see Figure 8. A pair of tubes 39 project inwardly from the cover plate 28 and communicate with holes 40 formed in said cover plate and these tubes 39 telescope into the tubes 37 and pass through packing glands 41 as shown in Figure 8. The tubes 37 are so arranged that they will communicate with the small slot 32 in the revolving disk 20 during the rotary movement of said disk.

A bracket 42 is carried by the cover plate and the outer portion thereof forms a bearing for the outer end of a shaft 43, the inner end of which is reduced as shown at 43' and has a rotatable fit in the tubular outer portion of the shaft 23. The shaft 43 carries the cranks 44 for the links 17 and a projection 45 extends from the inner end of the large part of the shaft 43 for cooperating with the projection 25 on the shaft 23 so that rotary movement of the shaft 43 will be communicated to the shaft 23 when the projections are in engagement with each other. A hand wheel 46 is connected to the outer end of the shaft 23 for partly turning the shaft 23 and the valve 20 when it is desired to reverse the engine and it will, of course, be understood that the projections 25 and 45 enable this reversing operation to be performed. As will be seen as the shaft 43 is being turned from the engine crankshaft 13 through means of the cranks 16 links 17 and cranks 44 the shaft 23 of the valve disk 20 will also be turned due to the engagement of the projection 45 on shaft 43 with the projection 25 on shaft 23 and the parts are so constructed and arranged that the engine will run in one direction when the hand wheel 46 has been turned to place the shaft 23 and the disk 20 in one position. Then when it is desired to reverse the engine the shaft 23 is turned by the hand wheel 46 to give the disk 20 a half turn to reverse its position relative to the slots or ports 6 so that the engine is reversed, this partial turning movement of the shaft 23 bringing the projection 25 into engagement with the opposite side of the projection 45.

60 An inlet pipe 47 extends from a source of supply of steam or the like to the chest and this pipe contains any suitable type of control valve 48.

As will be seen the steam or other fluid will enter the chest 4 through the pipe 47 and when the parts are in the position shown in Figure 2 some of the steam will pass through the slot 31 in the rotary valve disk 20, through the left slot 6 and passage 7 into the left end of the cylinder 2 so as to move the piston 8 to the right. The fluid previously introduced into the right end of the cylinder will escape through the exhaust port 18 until said port is covered by the piston. Then further movement of the piston tends to compress the fluid in the right end of the cylinder but this compression is relieved as one of the tubes 37 is in

communication with said end of the cylinder through the right hand passage 7, the right port 6 and the small slot 32 of the valve 20 and thus the fluid will pass through these parts and through the tube 39 and escape through the hole 40 in the cover plate 28. However, the tube 37 and the small slot 32 are so constructed and arranged that the slot 32 will pass out of register with the tube 37 before the piston reaches the end of its stroke to the right and thus some of the fluid will remain in the cylinder to act as a cushion for the last part of the movement of the piston. Then the large port 31 in the rotary disk 20 will come over the right hand slot 6 so that the fluid will pass from the valve chest through the slot 31 and slot 6 and right hand passage 7 into the right end of the cylinder 2 to force the piston 8 in the opposite direction and then the pressure in the left end of the cylinder will be relieved by the small slot 32 in the disk 20 coming into register with the other tube 37 of the disk 34.

It will, of course, be understood that the valve mechanism is operated from the shaft 13 through means of the cranks 16, links 17 and the cranks 44 and these parts may be of any suitable construction. I prefer to use a pair of links 17 and sets of cranks 16 and 44 for by doing so the links 17 and cranks 44 will pull each other off of dead center.

It will also be understood that when it is desired to reverse the engine it is simply necessary to turn the wheel 46 to rotate the shaft 23 a distance to bring the slot 31 in disk 20 opposite the other port 6 so that the fluid will be fed to the opposite end of the cylinder 2.

As will be seen the valve mechanism acts as a two-in-one valve means as it controls the flow of steam or other fluid to the ends of the cylinder and also acts to relieve compression in that end of the cylinder toward which the piston is advancing but such relieving action permits sufficient fluid to stay in the cylinder to act as a cushion for the piston.

It is thought from the foregoing description that the advantages and novel features of the invention will be readily apparent.

It is to be understood that changes may be made in the construction and in the combination and arrangement of the several parts, provided that such changes fall within the scope of the appended claims.

Having described the invention, what is claimed as new is:

1. In an engine actuated by compressible fluid and including a cylinder, a piston operating in the cylinder and said cylinder having a substantially centrally arranged outlet port and conduits leading from the ends of the cylinder, a valve chest, means for introducing fluid thereto, said chest having oppositely arranged elongated ports therein for communicating the chest with the conduits, a rotary disk in the chest having an outer elongated arcuate slot therein for uncovering portions of the ports of the chest during the rotary movement of the disk, said disk having an inner arcuate slot therein for uncovering the inner portions of these ports during the rotary movement of the disk, a stationary disk of smaller diameter than the first disk and contacting the portion thereof containing the inner slot, oppositely arranged tubular parts carried by the stationary disk and being alternately placed in communication with the chest ports by the inner slot of the rotary disk, means for connecting the tubular parts with the exterior of the chest and means for rotating the rotary disk.

2. In an engine actuated by compressible fluid and including a cylinder, a piston operating in the cylinder and said cylinder having a substantially centrally arranged outlet port and conduits leading from the ends of the cylinder, a valve chest, means for introducing fluid thereinto, said chest having oppositely arranged elongated ports therein for communicating the chest with the conduits, a rotary disk in the chest having an outer elongated arcuate slot therein for uncovering portions of the ports of the chest during the rotary movement of the disk, said disk having an inner arcuate slot therein for uncovering the inner portions of these ports during the rotary movement of the disk, a stationary disk of smaller diameter than the first disk and contacting the portion thereof containing the inner slot, oppositely arranged tubular parts carried by the stationary disk and being alternately placed in communication with the chest ports by the inner slot of the rotary disk, means for connecting the tubular parts with the exterior of the chest, means for rotating the rotary disk, and means for adjusting the rotary disk to reverse the engine.
3. In an engine which includes a cylinder having a substantially centrally arranged exhaust port, conduits leading from the ends of the cylinder and a piston in the cylinder, a valve chest having elongated oppositely arranged ports therein in communicating the chest with the conduits, each port tapering inwardly from a wide outer end, a rotary disk in the chest having an outer arcuate-shaped slot therein for uncovering the wide ends of the ports during the rotary movement of the disk and a smaller inner arcuate slot therein for uncovering the inner ends of the ports during rotary movement of the disk, a shaft connected with the disk and passing from the chest, a stationary disk of smaller diameter than the rotary disk, spring means for pressing the stationary disk against the rotary disk, said small disk covering that part of the rotary disk containing the inner slot while leaving that part of the disk containing the large slot uncovered, a pair of tubular parts carried by the stationary disk and having their inner ends uncovered by the inner slot during rotary movement of the disk, telescopic means engaging the tubular parts and leading to the exterior of the chest and means for rotating the shaft connected with the rotary disk, said means including a shaft telescoping into the shaft of the rotary disk, projections on the two shafts engaging each other when the disk shaft is being rotated from the other shaft while permitting the disk shaft to be adjusted to reverse the movement of the engine, manually operated means for adjusting the disk shaft relative to the second shaft and means for rotating said second shaft from the engine.

FARRIER CORMIER.
